COMBINATION PENCIL HOLDER

Alfred E. Brandon, New York, N. Y.

Original application July 19, 1934, Serial No. 735,997. Divided and this application January 21, 1936, Serial No. 60,042

8 Claims. (Cl. 120—9)

This application is a division of application No. 735,997, filed July 19, 1934.

This invention relates to improvements in pencil holders, and is more particularly directed to the kind for ordinary pencils, crayons, chalk, or the like rod shaped implements; and the objects of the improvement are:

First; To provide a novel means for retaining a pencil in the holder, whereby said pencil can readily be adjusted to the desired position for use; and also can be conveniently used up within an inch of its length therewith.

Second; To provide an improved means for retaining and releasing of a pencil, whereby accidental breaking of pencil points, when usual adjustments for use are made, are eliminated.

Third; To provide a holder for rod shaped writing implements of simple and inexpensive construction, durable and efficient in operation.

Other and further objects and advantages of the invention will be apparent as the description proceeds.

The accompanying drawing shows, for purposes of illustrating the present invention, one embodiment in which the invention may take form, together with modification of certain parts, it being understood that the drawing is illustrative of the invention rather than limiting the same.

10 In the drawing:

Figure 1 is an elevational view of a holder, constructed according to the invention, with a pencil and eraser when it is being used.

Fig. 2 is a longitudinal section of the holder on the line 2—2 of Fig. 1, showing in elevation the pencil, the eraser and the clamping or wedging element in place.

Fig. 3 is the same as Fig. 2, but showing the pencil when it is not being used.

Fig. 4 is an enlarged transverse section of the holder on the line 4—4 of Fig. 1.

Fig. 5 is an enlarged fragmentary sectional view of the holder on the line 5—5 of Fig. 4, showing the clamping or wedging means or element and its parts in place when retaining a pencil or the like rod shaped implement in the holder.

Fig. 6 is the same as Fig. 5, but showing the clamping or wedging means or element and its parts in position when releasing a pencil or introducing same in the holder.

Fig. 7 is an enlarged plan view of the clamping or wedging element when looking in the direction of the arrow 7 in Fig. 8.

Fig. 8 is a side view of Fig. 7.

Fig. 9 is an elevational view of a modified holder, constructed according to the invention.

Fig. 10 is a longitudinal section thereof on the line 10—10 of Fig. 9, showing in elevation a pencil and the clamping or wedging element in place; and also a portion of the holder serving as pencil point protector with an eraser in elevation therein.

Fig. 11 is the same as Fig. 10, but the pencil point protector serving as a handle, and the eraser being omitted.

Referring more particularly to the drawing the numeral 1 designates a metal casing of tubular form the upper and lower ends open.

A longitudinal recess 2, formed in the wall surfaces of the casing, and adapted to receive a metal or the like wedge shaped element 3 movable longitudinally therein.

The wedge shaped element has a pair of spaced parallel upstanding wings or hangers 4, connected at their free ends by a bar or pin 5, which is freely rotatable in an aperture 6, formed in the short arm of a bell crank 7, disposed in a recess or aperture 8 formed an extension of the recess 2.

The bell crank having its fulcrum on another bar or pin 9 secured in the wall of the recess or casing facilitates up and downward movements of the long arm or lever, and causes the movements of the wedge shape element.

In Fig. 6 it can be seen, that by merely raising the long arm or lever the wedge shaped element is drawn up and forced rearward or from the open end of the casing, leaving the inner surfaces of the holder unobstructed to receive a pencil 10, or a rod shaped eraser 11, each of which is shown in Figs. 2 and 3 as being circular in transverse section, but may be of polygonal or other transverse section.

Obviously, upon lowering the long arm or lever in place, the under surfaces of the wedge shaped element contacts the pencil 10 or eraser 11, while the short arm forces the pin 5 forward or toward the open end of the casing effecting a sliding movement of the wedge shaped element to a point sufficient for holding the pencil in the casing.

Between the upstanding wings or hangers 4 is a pressed up spring element 12, coacting or contacting the bottom or under surfaces of the short arm, whereby the long arm or lever is forced to remain in place, and also causes the entire length of the under surfaces of the wedge shaped element to bear on the pencil evenly.

The casing or holder is of a convenient length

for use, and is provided with a washer 13 for sturdiness of its wall.

14 is the usual pocket clip disposed in the usual manner.

5 A modified form of construction is shown in Figs. 9, 10 and 11. Here the casing shown is of thick walls yet of light materials such as is being used for fountain pens.

10 The lower portion 15 is adapted to receive the pencil 10a, held in position by the wedge shaped element 3a, which functions in similar manner as previously described in an interior recess 16; and the long arm or lever of the bell crank 1a in an exterior recess 17. Both recesses 16 and 17 15 being cut in the wall of the casing.

The portion 15, being too short for convenient use or handling in writing, drawing or the like, is provided with an extension portion 15a. When it is in position shown in Figs. 9 and 10, it will 20 be noted that it functions as a pencil protector; while in Fig. 11 it is a handle.

25 Both portions 15 and 15a may be provided with suitable means for detachably securing the one to the other as for instance, slightly tapering both ends of portion 15 and providing threads 18 cut in the exterior wall surfaces; and adapting one open end of portion 15a to receive either threaded end of portion 15, as indicated in the drawing. The other end of portion 15a may be provided 30 with internal threads 19 to receive an eraser 20 having a wood or the like enclosure 21 having threads 22, adapted to receive the threads 19 as shown on the drawing, but forms no part of the present invention.

35 The inward movement of the eraser 20 may be stopped by means of pin 23 disposed transversely in the wall.

14a is the usual pocket clip secured in the usual manner.

40 It is obvious that the invention may be embodied in many forms and constructions within the scope of the claims and I wish it to be understood that the particular form shown is but one of the many forms. Various modifications 45 and changes being possible, I do not otherwise limit myself in any way with respect thereto.

I claim:

1. The combination, in a pencil holder, of a 50 tubular casing with open ends having a recess laterally of the inner surface, said recess extending from the vicinity of one open end to a portion inwardly thereof, an aperture formed in the wall of the casing, a wedge shaped element in said recess and parts in said aperture cooperative with said element for slidably engaging a pencil or the like shaped implement in the casing.

2. The combination, in a pencil holder, of a 55 tubular casing with an open end having, interiorly, a recess near the open end, an aperture centrally of the recess, a wedging element actuatable in the said recess, and means cooperative therewith disposed in the aperture and being arranged to effect slidable movements of the 60 wedging element for retaining a pencil or the like rod shaped implement in the casing.

3. The combination, in a pencil holder, of a tubular casing having an open end, an interior recess adjacent the open end, a wedging element actuatable within the recess, an aperture centrally of the recess provided with means supporting said wedging element therefrom, whereby when said supporting means actuates the wedging element slidably in the recess an ordinary pencil or the like rod shaped implement 5 10 may be held in the casing.

4. A combination pencil holder comprising a tubular casing having an open end, a recess formed in the tubular wall adjacent the open end, wedge means in said recess, an aperture through the tubular wall into said recess, exteriorly accessible means pivoted in the aperture for effecting, interiorly, movements of the wedge means in the said recess to grip a pencil or the like rod shaped implement in the casing. 15

5. A pencil holder comprising a tubular casing 20 with open end, an interior recess adjacent the open end, wedge means movable in the interior recess, an aperture through the wall of the casing, exteriorly accessible means in the aperture for regulating the movements of the wedge 25 means, whereby a pencil or the like rod shaped implement in the casing may be kept in desired position and prevented from accidental longitudinal movement in respect thereto.

6. A combination pencil holder comprising a 30 tubular casing having an open end, an interior recess, wedging means movable in the interior recess for wedging a pencil or the like rod shaped implement against the inner surfaces of the casing, an aperture through the wall of the casing, 35 exteriorly accessible means in said aperture cooperative with the wedging means whereby the pencil or the like rod shaped implement may be released from or retained in the casing.

7. A combination pencil holder comprising a 40 tubular casing having open ends, a recess formed in the wall near one end, wedge means in said recess for contacting with the body of a pencil or the like rod shaped implement, an aperture through the wall of the casing, exteriorly accessible means in said aperture connected to and coacting with the first means to effect wedging pressure between the pencil and the casing, and other means coacting with said first and second means to control the said wedging pressure. 45 50

8. In a combination pencil holder, the combination of a substantially cylindrical shaped casing having the bore thereof extended laterally to form a recess, a wedging element positioned substantially within said recess and actuatable, 55 freely therein, the lower portion of said wedging element cooperating with the inner surface of the casing to releasably retain a pencil or the like rod shaped implement in said casing, and means pivotally mounted in said recess cooperating with the upper portion thereof for regulating the pressure of said element upon the body 60 of the pencil.

ALFRED E. BRANDON.
